UNITED STATES PATENT OFFICE.

HARRMON BUSSEL, OF ROSS, IOWA.

END-GATE FOR WAGONS.

SPECIFICATION forming part of Letters Patent No. 429,011, dated May 27, 1890.

Application filed March 8, 1890. Serial No. 343,169. (No model.)

To all whom it may concern:

Be it known that I, HARRMON BUSSEL, a citizen of the United States, and a resident of Ross, in the county of Audubon and State of Iowa, have invented certain new and useful Improvements in End-Gates for Wagons; and I do hereby declare that the following is a full, clear, and exact description of the invention, which will enable others skilled in the art to which it appertains to make and use the same.

My invention relates to improvements in end-gates for wagons and other similar vehicles.

15 The object of my invention is to provide an end-gate for wagons which is simple and economical in construction, and which can also be readily removed from the wagon and used as a seat, a dumping-board, or hog-chute, as 20 may be desired.

It is the object, also, to provide an improved construction of locking or holding mechanism, whereby the gate may be securely held in a closed position, and which can be lowered 25 without getting out of the wagon.

The invention consists in the several features of construction and new combinations of parts hereinafter fully described, and then definitely pointed out in the appended claims.

30 In the accompanying drawings, in which similar reference-numerals indicate similar parts in all the views, Figure 1 is a side elevation showing a wagon-body with my improved end-gate applied thereto, said gate being in a closed and locked position. Fig. 2 is a similar view showing the gate partly lowered. Fig. 3 is an end view of the same. Fig. 4 is a plan view.

In the said drawings, the reference-numeral 40 1 designates the sides of the wagon-body, and 2 a cross-bar, to which the ordinary springs may be secured.

The numeral 3 designates the end-gate, the ends of which are flush with the outer sides 1 45 of the wagon. At each end of the gate 3 are secured the triangularly-shaped side pieces 3^a, which project forwardly and embrace the sides of the wagon. To the cross-bar 2 are secured the pivots by which the gate is connected with the body. These pivots consist of horizontal metal bars, which extend rear-

wardly just beyond the gate, when they are bent upwardly and then transversely, forming short arms or pivots 4. These pivots or arms are inserted in eyes 5 in the plates 6, 55 secured to the end-gate, so that the latter can be readily swung thereon so as to be raised or lowered. It will be noted that the arms 4 project in the same direction, so that they can be readily disengaged from the eyes by simply 60 sliding the gate in a lateral direction, and can be as readily engaged therewith by a reverse movement.

At the upper edges of the sides 1, near the rear ends thereof, is secured a plate 7, to the 65 free outwardly-projecting end 8 of which is pivoted a rearwardly-extending arm 9, the rear end of which is provided with a curved lug 10. Pivoted to this arm 9, at the rear end thereof, is another arm 12, which is provided 70 with a backwardly-curved extension or arm 13, forming a hook, which engages with a pin 14 on the end-gate, and thus holds the latter securely in place when in a closed position. The outer free end of the pin 14 is bent or 75 turned upwardly, forming a short projecting arm, which prevents the hook from laterally sliding off the pin. The free end of arm 13 is bent downwardly and backwardly, forming a hook 15, which engages with the pin 14 when 80 the end-gate is partly lowered, as in Fig. 2, and retains the same in position, the movement of arms 9 and 13 being limited by the lug 10. The end of arm 13 may be provided 85 with a short arm 16, which forms a handle for operating the same.

The operation of my invention will be readily understood. When the end-gate is in the closed position shown in Fig. 1, the hook 13 engages with pin 14 and holds it securely in 90 place. When it is desired to retain the gate in a partly lowered position, as in Fig. 2, the hook 13 is disengaged from pin 14 and the gate lowered until the pin 14 engages with hook 15, by which it is securely held. To 95 completely lower the gate hook 15 is disengaged from said pin and allowed to drop down. Upon the side pieces 3^a are secured plates 17, having outwardly-projecting lugs 18, between which the arm 13 may be inserted 100 and retained against accidental disengagement with pin 14 when the gate is closed.

It will be understood from the above description that the gate can be readily disengaged from the wagon-body when desired and used as a seat or for any other purpose to 5 which it may be adapted. When used as a seat, the plates 6 will prevent lateral movement of the same, while the triangular pieces 4 will form the sides of the seat.

Having thus described my invention, what 10 I claim is—

1. The combination, with a wagon-body and the pivoted end-gate 3, provided with pins 14, of the jointed arms 9 and 13, arm 9 being secured to the wagon-body and arm 13 provided 15 with hooks 13 and 15, substantially as described.

2. The combination, with a wagon-body and the end-gate 3, provided with pins 14, of the arm 9, pivoted to the wagon-body and pro-

vided with the curved lug 10, and the arm 13, 20 provided with hooks 13 and 15, substantially as described.

3. The combination, with a wagon-body and the end-gate 3, having pins 14 and triangularly-shaped side pieces 3^a, provided with plates 17, having lugs 18, of the arm 9, pivoted to the wagon-body and provided with lugs 10, and the arm 13, pivoted to arm 9 and having hooks 13 and 15, and handle 16, substantially as de- 25 scribed. 30

In testimony that I claim the foregoing as my own I have hereunto affixed my signature in presence of two witnesses.

HARRMON BUSSEL.
